UNITED STATES PATENT OFFICE.

EUGENE B. GRAY, OF NEW YORK, N. Y.

DESIGN FOR A FOOT-BRAKE DOG.

SPECIFICATION forming part of Design No. 30,269, dated February 28, 1899.

Application filed January 30, 1899. Serial No. 703,908. Term of patent 7 years.

To all whom it may concern:

Be it known that I, EUGENE B. GRAY, of the city of New York, borough of Manhattan, in the county and State of New York, have invented and produced a new and original Design for a Foot-Brake Dog, of which the following is a full, clear, and exact specification.

Reference is to be had to the accompanying drawings, forming a part of this specification, in which similar characters of reference indicate corresponding parts in all the views.

Figure 1 is a perspective view of a foot-brake dog, showing my design. Fig. 2 is a plan view of the same. Fig. 3 is a transverse section of the same on the line 3 3 in Fig. 2, and Fig. 4 is a like view of the same on the line 4 4 in Fig. 2.

The design in its entirety consists of the pawl-body A, formed with the apertured fulcrum portion A', and the dog-arm A² and the

handle A³, extending at an angle from the fulcrum portion A', the dog-arm A² being ornamented by an integral guard B, extending along and rising from the outer edge of the said arm A² and projecting beyond the point A⁴ thereof and following the curvature of the dog-arm A² and approximately triangular in cross-section, as shown in Figs. 3 and 4.

The leading feature of the design consists of the guard B on the dog-arm and extending beyond the same.

I claim—

The design for a foot-brake dog herein shown and described.

EUGENE B. GRAY.
